UNITED STATES PATENT OFFICE.

JOSEPH KAY, OF WINDHILL, SHIPLEY, ENGLAND, ASSIGNOR TO GEORGE HODGSON,
LIMITED, OF BRADFORD, ENGLAND, A FIRM.

LOOM PATTERN-CHAIN.

1,102,669.

Specification of Letters Patent.

Patented July 7, 1914.

Application filed September 7, 1912. Serial No. 719,050.

To all whom it may concern:

Be it known that I, JOSEPH KAY, a subject of the King of Great Britain, and resident of 39 Fairbank street, Windhill, Shipley, in the county of York, England, have invented a new and useful Improvement in Loom Pattern-Chains, of which the following description, which has reference to the accompanying sheet of drawings, is a specification.

My invention relates to loom pattern chains of the type which carry projecting parts to effect changes in the positions of the loom mechanism for the varied purposes for which said mechanisms may be employed, and my said invention relates more particularly to that type or class of said devices which are produced of sheet metal.

20 The object of my invention is the production of said pattern chains of such a character as will enable the upper surface and side walls thereof to conform to the shape of the ordinary wood lags at present in use, 25 and yet be light and firm and afford ready means for the fixing in position thereon or the removal therefrom of the raised surfaces or pegs for purposes well known, while the whole is rendered firm and durable to 30 resist any of the forces that are brought to bear upon them throughout their several and varied operations. The parts of said devices which are subject to wear are of such a character as best to resist said wear 35 and the several parts may be produced at comparatively little cost.

In order that my said invention may be readily understood I have hereunto appended a sheet of drawings illustrative thereof, 40 to which, by figures and letters reference is made in the following description:

Figures 1 and 2 are respectively sectional side elevation and plan of parts constructed in accordance with my invention, the 45 same being drawn to a reduced scale as compared with the other figures. Fig. 3 is an elevation showing the end of a lag and one projecting piece of peg mounted in position thereon. Fig. 4 is a plan of the parts shown 50 by Fig. 3, with a certain holding device in position as when in use. Fig. 5 is a similar view to Fig. 4 but shows said holding device and the link in connection therewith in position as when freed for detachment. Fig. 55 6 illustrates a short portion of a strip of

metal pierced or stamped with the necessary openings so that when subsequently bent into the shape desired my improved lag is produced. Fig. 7 is an end elevation of parts shown by Fig. 3 as seen in the direction indicated by the arrow *a*. Figs. 8 and 9 illustrate a part in detail which forms coupling means to secure one lag to another. Fig. 10 is an end elevation of the parts shown by Fig. 5. Fig. 11 is a similar view 65 to Fig. 3 but shows the parts in position as illustrated by Figs. 5 and 10. Fig. 12 is a drawing in detail of a part hereinafter described. Figs. 13 and 14 are side and edge views of a strengthening part which is 70 mounted in the interior of the bent strip hereinafter explained.

In carrying my invention into effect a strip *b* of sheet metal (see Fig. 6) of the necessary width is taken and perforated 75 with the series of openings, hereinafter referred to, and it is then bent so that portions at the edges *b'*, *b*², will form side walls, while the part between will form the upper surface of the lag in order to give said 80 lag the outside contour of the present wooden lag, such contour being shown by Figs. 7 and 10. Perforated stay pieces *c* are fixed within or between said walls *b'*, *b*² as by having their projecting parts *c'* 85 taking through openings *c*² in the strip *b* there to be riveted (as will be understood) in order to support and fortify the side walls *b'*, *b*² as well as to act as guides or protecting means for preventing the said side walls 90 of one lag entering the interior of one or other of its neighboring lags as the same are carried through their respective paths when in operation. Through the strip *b* are formed perforations *d* in such positions 95 thereon that when said strips *b* have their edges *b'*, *b*², bent as above described, said openings *d* will fall on the edge of the lag to receive the bent ends *f'*, *f*² of the projecting piece *f* which I employ as the indicating means or pattern surface instead of the wooden or metal pegs customarily used in conjunction with the ordinary wooden lags. These projections *f* are formed of strips of metal preferably spring steel, so 100 that by their bent ends *f'*, *f*² taking within the openings *d* on the opposite edges of the lag *b* they are held in position therein by their own recoil, causing the hooked ends (see Fig. 7) to enter and be retained with- 110

in their respective slots *d*. The projections or spring pieces *f* thus formed while acting efficiently for the purpose for which they are produced also are hardened to resist wear.

As means for coupling the series of lags *b* together in order to produce the pattern chain in a manner well known, I make use of bent or hooked pieces *g* which are preferably of considerable width, to take through openings *h* formed in said lags *b* in order that their hooked ends may lay hold of coupling links *k*. To retain these hooked parts *g* in position a spring actuated pin *m* enters 10 an opening *g'* formed therein while passing through an opening *m'* formed in the lag *b*, so that said hooked part *g* is thus secured as desired. The links *k* coupling the hooked parts to each other preferably have square 15 openings made through them and the sides of these openings are straight so as to be in contact with the full width of each hooked part *g* whether said link is turned for one side to be connected therewith or to have 20 another of such sides in connection, hence the wearing surfaces of the links *k* as well as those of the hooked parts *g* are as extensive as desired in order to resist wear.

Such being the nature and object of my 25 said invention, what I claim is:—

1. A sheet metal lag for loom pattern chains, comprising a strip having its edge portions bent downwardly and presenting flanges at an abrupt angle to the middle portion, said flanges having slots below their angular junctions with the middle portion, and arched strips of spring metal having inwardly bent ends sprung into said slots.

2. A sheet metal lag for loom pattern

chains, comprising a strip having its edge 40 portions bent downwardly and presenting flanges at an abrupt angle to the middle portion, said flanges having slots below their angular junctions with the middle portions, cross pieces secured between the flanges to 45 strengthen the lag, and arched strips of spring metal having inwardly bent ends sprung into said slots.

3. A sheet metal lag for loom pattern chains, comprising a strip having its edge 50 portions bent downwardly and presenting flanges at an abrupt angle to the middle portion, said flanges having openings near their ends and having slots intermediate said openings, said openings and slots being below the plane of the middle portion, arched strips of spring metal having inwardly bent ends sprung into the slots, and strips extending through the openings near the ends of the flanges, the last mentioned strips being adapted to be connected to similar strips of other lags to compose the pattern chain.

4. A sheet metal lag for loom pattern chains, comprising a strip having its edge 55 portions bent downwardly and presenting flanges, said flanges having openings near their ends, strips extending through said openings, said strips having bent ends, and links having rectangular openings connected with the bent ends of said strips.

In testimony whereof I have hereunto affixed my signature in the presence of two witnesses.

JOSEPH KAY.
